UNITED STATES PATENT OFFICE.

PAOLO CHILLEMI, OF SCHENECTADY, NEW YORK.

WASHING-MACHINE.

1,363,493.

Specification of Letters Patent. Patented Dec. 28, 1920.

Application filed September 10, 1919. Serial No. 322,885.

To all whom it may concern:

Be it known that I, PAOLO CHILLEMI, a subject of Italy, residing at Schenectady, in the county of Schenectady and State of New York, have invented new and useful Improvements in Washing-Machines, of which the following is a specification.

Reference may be had to the accompanying drawings, and the reference characters marked thereon, which form a part of this specification. Similar characters refer to similar parts in the several figures therein.

This invention relates to a type of clothes-washing-machine having an oscillating dasher, with clamping mechanism for detachably mounting clothes thereupon whereby the clothes are repeatedly dashed into the wash-water or suds in the operation of the machine.

The principal object of my invention is to automatically cause a more effective movement of the dasher of which its simple oscillating movement is a component.

Other objects will appear in connection with the following description.

Figure 1 of the drawings is a view in side elevation of my improved washing-machine with the tub shown in vertical longitudinal section.

Fig. 2 is a central vertical section taken on the broken line 2-2 in Fig. 1, through the upper end of the rocker and the mechanisms mounted thereon.

Fig. 3 is a view of the inner side of the pawl-actuated cam-wheel by means of which the bearing-box for the crank-pin is alternately locked to and released from the dasher-actuating slide.

Fig. 4 is a view partly in elevation and partly in vertical cross-section of the machine as seen from the right-hand side of Fig. 1.

Fig. 5 is a view in side elevation, partly broken away and shown in section, of the mechanism shown in Fig. 2.

Fig. 6 is a horizontal section taken on the broken line 6-6 in Fig. 4 viewed from above.

Fig. 7 is a similar view with the dog-operating crank-disk removed.

Fig. 8 is a bottom plan view of the crank-disk detached.

Referring to the drawings wherein the

invention is shown in preferred form, 1 is a tub supported by legs, 2, mounted upon casters, 2^a, the tub being of elongated form.

The top-plate, 3, extends across the middle portion of the tub, leaving openings, 4, along each side of the board for access to the interior of the tub.

These openings, 4, are adapted to be closed by lids or doors, 5, hinged at 6 upon the tub and adapted to be swung down alongside the tub when desired, as shown at the left-hand side of Fig. 1.

The bottom of the tub is preferably corrugated as shown at 7.

The clothes are carried by a dasher comprising a frame, 8, carrying a roller, 9, and clamp-bar, 10, adjustably mounted upon the frame, 8, whereby the clothes can be clamped between the roller, 9, and the clamp-bar, 10.

The side members of the frame, 8, have along their inner sides teeth, 11, adapted to be engaged by a pair of dogs, 12, slidably mounted upon the clamp-bar and adapted to be forced into and out of engagement with the teeth, 11, by means of a hand-operated crank-disk, 13, carrying crank-pins, 14, engageable respectively with offset portions, 15, on the respective dogs, 12.

The dasher is carried by a slide, 16, reciprocable in a slideway, 17, which extends longitudinally of a rocker, 18, rockably mounted at 19, upon a bracket, 20, depending from the top-plate, 3, whereby oscillating movements of the slide 16, longitudinally of the tub are permitted.

The slide, 16, is provided with a longitudinal slot, 21, forming a slideway for a crank-pin bearing-box, 22, which forms a bearing for a crank-pin, 23, carried by a crank-arm, 24, fixed upon a shaft, 25, rotatively mounted in bearings in uprights, 26, erected from the top-plate, 3.

The shaft, 25, is connected by gears, 27, with a counter-shaft, 28, also rotatively mounted in bearings in said uprights, 26.

The shaft, 28, may be operated by power or hand in any known manner.

I have shown a hand-wheel, 29, fixed upon said shaft, 28, whereby the same may be operated.

The crank-pin bearing-box, 22, is provided with a pair of slideway apertures, 30, for a pair of dogs, 31, which dogs in a certain

position of said bearing-box relatively to the slide, 16, are adapted to enter and engage openings, 32, in said slide whereby the slide and the crank-pin bearing-box are locked in fixed relation to each other, and when so locked together the slide will partake of the movement of the crank-pin bearing-box toward and from the axis of oscillation of the rocker, 18, so that a longitudinal reciprocating movement will be imparted to the slide and dasher relatively to the rocker, 18, while the rocker and the slide with the dasher are oscillated by the continuous movement of the crank 24.

15 When the dogs, 31, are withdrawn from the openings, 32, in the slide, the slide is left free from the bearing-box permitting the bearing-box to reciprocate along the slide-way-slot, 21, in the slide as the crank is continuously operated, without longitudinal movement of the slide relatively to the rocker, 18.

20 For certain purposes of the invention, the dogs, 31, may be forced into the respective openings, 32, in the slide and withdrawn therefrom in any known manner.

25 I have shown a preferred form of mechanism whereby this result is accomplished automatically in the operation of the machine, which mechanism is shown in detail 30 in Figs. 2, 3 and 5.

30 In this construction the dogs, 31, are forced inwardly and outwardly by means of a lever, 33, fulcrumed at 34, upon a bracket, 35, extending upwardly from the crank-pin bearing-box, 22, the lower end of said lever having fork-members, 36, which respectively engage recesses or openings, 37, in the respective dogs, 31.

40 The upper end, 38, of said lever, 33, is in the path of a cam, 39, on a cam-wheel, 40, rotatively mounted upon a spindle, 41, projecting laterally from the bracket, 35.

45 A coil-spring, 42, interposed between the bracket, 35, and the upper end of the lever, 33, tends to hold the upper end of the lever against the cam, 39, and to force the dogs, 31, inwardly into the openings, 32, in the slide when the lever is released from the influence 50 of the cam, 39, and the bearing-box is in the proper position relatively to said slide.

55 A portion of the inner face of the cam-wheel, 40, is cut-away at 43, to permit the lever, 33, to be thus actuated by the spring, 42, at certain times. At certain other times when the upper end of the lever, 33, is engaged and forced inwardly by the cam, 39, against the force of the spring, 42, the dogs, 31, are withdrawn and held withdrawn from the respective openings, 32, in the slide.

60 The cam-wheel, 40, is automatically rotated by a step-by-step movement in the operation of the machine by engagement of a dog, 44, with ratchet-teeth, 45, on the cam-

wheel, said dog being mounted upon the rocker, 18, in position to engage said ratchet-teeth during the latter part of each movement of the crank-pin bearing-box toward the axis of oscillation of the rocker. 70

A hand-actuated dog, 46, is mounted upon the top-plate, 3, in position to be forced into and out of engagement with the gear-wheel, 27, on the shaft, 28, whereby when desired said gear may be locked against rotative 75 movement with the dasher held in any desired position for convenience in inserting and removing the clothes.

The operation of the machine is as follows: 80

The operating members of the machine are locked against movement by a dog, 46, with the dasher in convenient position for inserting the clothes which position is preferably adjacent to one of the openings, 4. 85

The dogs, 12, on the clamp-bar, 10, are withdrawn by operation of the crank-disk, 13, permitting the clamp-bar to be separated from the roller, 9, to permit the clothes to be freely inserted between the roller and the 90 clamp-bar.

The clamp-bar is then forced toward the roller, 9, to clamp the inserted clothes against the roller, in which position the clamp-bar is secured by forcing the dogs, 12, 95 outward into engagement with the teeth, 11, on the dasher-frame by reverse movement of the crank-disk, 13.

The tub having been supplied with water or suds, the doors, 5, are closed and the shaft, 100 28, is rotated by means of the hand-wheel, 29, to impart a continuous movement to the crank, 24, and a step-by-step movement to the cam-wheel, 40.

So long as the cam, 39, on the cam-wheel, 105 40, holds the upper end of the lever, 33, in innermost position the lower fork-end of said lever will hold the dogs, 31, disengaged from the openings, 32, in the slide; and as the crank is continuously operated its bearing-box will slide freely inwardly and outwardly along the slide-way slot, 21, in the slide without imparting a longitudinal slide-movement to the slide. 110

When thus operated the slide remains in 115 substantially fixed relation to the rocker, 18, and a simple oscillating movement is imparted to the dasher longitudinally of the tub.

As the operation of the machine continues the step-by-step movement of the cam-wheel, 40, causes its cut-away portion, 43, to be brought opposite the upper end of lever, 33, releasing said lever to the action of the coil-spring, 42, tending to force the 125 lower fork-end of said lever inward and the dogs, 31, to enter the openings, 32, in the slide when the dogs are brought by the movement of the bearing box opposite said respective openings. The continued opera- 130

tion of the machine then causes the slide, 16, which is in fixed relation to the bearing-box to partake of the movement of the bearing-box toward and from the axis of oscillation 5 of the rocker, 18, thereby imparting to the slide, 16, a longitudinal reciprocating slide-movement relatively to the rocker, 18, whereby the dasher and clothes carried thereby are reciprocatingly moved toward 10 and from the axis of oscillation of the rocker, while also being oscillated longitudinally of the tub.

The slide-movement thus imparted to the slide, 16, is indicated by dotted lines in 15 Fig. 1.

In Fig. 2 the cam-wheel, 40, and lever, 33, are shown in position to hold the dogs, 31, withdrawn from the openings, 32, in the slide.

In Fig. 5 the lever, 33, is shown released from the control of the cam-wheel, 40, with the dogs, 31, held by the lever in engagement with the openings, 32, in the slide.

In the continued operation of the machine, 25 the dasher and clothes carried thereby can thus for a predetermined number of oscillations of the dasher be given a simple oscillating movement longitudinally of the tub, and for a certain number of oscillations of 30 the dasher can be given a more complex movement, the resultant of the simple oscillating movement of the dasher and the longitudinal reciprocating movement of the slide, 16.

I have shown the cam-wheel, 40, provided 35 with twelve ratchet-teeth, 45, and with its cam-portion cut-away at 43, opposite four of said teeth. By this arrangement, in the continued operation of the machine the dasher will be given eight simple oscillations, then four oscillations accompanied by 40 longitudinal movement of the slide, 16, then eight simple oscillations and so on indefinitely.

Any desired relative number of simple 45 oscillations of the dasher can be obtained by providing the cam-wheel, 40, with more or less ratchet-teeth, and by extending the cut-away portion, 43, of the cam to a greater or less extent.

For certain purposes of the invention, the dasher may be of any known form.

A coil-spring, 47, confined under compression between the cam-wheel, 40, and the 55 bracket, 35, frictionally holds the cam-wheel from accidental movement while the cut-away portion, 43, of the cam is opposite the upper end of lever, 33.

What I claim as new and desire to secure 60 by Letters Patent is—

1. In a washing-machine and in combination, a rocker having a longitudinal slideway; a slide reciprocable in said slideway in the rocker and provided with a longitudinal slot; a crank having a crank-pin; a

crank-pin bearing-box slidably mounted in the slot in said slide; means for operating said crank; and means whereby said bearing-box is at certain times secured in fixed relation to said slide, and at certain other 70 times is left free to reciprocate in said slot in the slide.

2. In a washing-machine and in combination, a rocker having a longitudinal slideway; a slide reciprocable in said slideway 75 in the rocker and provided with a longitudinal slot; a crank having a crank-pin; a crank pin bearing-box slidably mounted in the slot in said slide; means for operating said crank; and automatic means whereby 80 said bearing-box is at certain times secured in fixed relation to said slide and at certain other times is left free to reciprocate in said slot in the slide.

3. In a washing-machine and in combination, a rocker having a longitudinal slideway; a slide reciprocable in said slideway in the rocker and provided with a longitudinal slot; a crank having a crank-pin; a crank pin bearing-box slidably mounted in 90 the slot in said slide; means for operating said crank; a dog whereby said bearing-box and said slide can at certain times be secured in fixed relation to each other; and means automatically actuated by the movement of said bearing-box whereby said dog 95 is at predetermined intervals moved into and out of position to secure together said bearing-box and slide.

4. In a washing-machine and in combination, a rocker having a longitudinal slideway; a slide reciprocable in said slideway in the rocker and provided with a longitudinal slot, and having dog-engaging means; a crank having a crank-pin; a crank-pin 100 bearing-box slidably mounted in the slot in said slide; means for operating said crank; a dog mounted on said bearing-box engageable at certain times with said dog-engaging means on the slide; a dog-operating member 105 carried by said bearing-box whereby said dog is moved into and out of engagement with said dog-engaging means on the slide; mechanism including a cam carried by said bearing-box whereby said dog-operating member is actuated at certain times; and pawl-and-ratchet cam-operating mechanism actuated by the movements of said bearing-box. 110

5. In a washing-machine and in combination, a rocker having a longitudinal slideway; a slide reciprocable in said slideway in the rocker and provided with a longitudinal slot; and having dog-engaging means; a crank having a crank-pin; a crank-pin 120 bearing-box slidably mounted in the slot in said slide; means for operating said crank; a dog mounted on said bearing-box engageable at certain times with said dog-engaging means on the slide; a dog-operating lever 125

pivoted upon said bearing-box whereby said dog is moved into and out of engagement with said dog-engaging means on the slide; a cam-wheel rotatably mounted on said bearing-box and having ratchet-teeth, and a cam engageable with said lever; a pawl mounted upon said rocker engageable with

said ratchet-teeth by the movement of said bearing-box; and a spring acting upon said lever in opposition to said cam. ¹⁰

In testimony whereof, I have hereunto set my hand this 6th day of September, 1919.

PAOLO CHILLEMI.
